(57) **CLAIM**

The ornamental design for a light fixture, as shown and
described.

DESCRIPTION

FIG. 1 is a perspective view of a light fixture in accordance
with my design;

FIG. 2 is a front elevation view of the light fixture in accordance
with my design;

FIG. 3 is a side elevation view of the light fixture in accordance
with my design, the opposite side being a mirror image
of that shown;

FIG. 4 is a top plan view of the light fixture in accordance with
my design; and,

FIG. 5 is a bottom plan view of the light fixture in accordance
with my design.
